(57) **CLAIM**

The ornamental design for a shift reel, as shown and described.

DESCRIPTION

FIG. 1 is a top and rear perspective view of a shift reel of our new design.

FIG. 2 is a top and front perspective view thereof.

FIG. 3 is a bottom and rear perspective view thereof.

FIG. 4 is a bottom and front perspective view thereof.

FIG. 5 is a top view thereof.

FIG. 6 is a bottom view thereof.

FIG. 7 is a left side view thereof.

FIG. 8 is a right side view thereof.

FIG. 9 is a rear view thereof; and,

FIG. 10 is a front view thereof.

(Continued)

The broken lines in the drawings are used to show portions of the shift reel and form no part of the claimed design.

1 Claim, 5 Drawing Sheets
